COMBINED JACK AND BUMPER GUARD

David B. Cohane, Flushing, N. Y.

Application March 23, 1954, Serial No. 29,661

Term of patent 14 years

(Cl. D14—6)

To all whom it may concern:

Be it known that I, David B. Cohane, a citizen of the United States, residing in Flushing, county of Queens, and State of New York, have invented a new original, and ornamental Design for a Combined Jack and Bumper Guard, of which the following is a specification, reference being had to the accompanying drawing, forming part thereof, in which:

Fig. 1 is a frontal perspective view of a combined jack and bumper guard showing my new design; and

Fig. 2 is a left side elevational view thereof, the view from the opposite side being identical.

The fragmentary dotted line disclosure of a bumper is shown only for the purpose of illustration.

I claim:

The ornamental design for a combined jack and bumper guard, substantially as shown and described.
